(57) **CLAIM**

The ornamental design for a flat antenna for digital television reception, as shown.

DESCRIPTION

FIG. 1 is a front elevational view of a flat antenna for digital television reception showing our new design.

FIG. 2 is a right side view thereof;

FIG. 3 is a left side view thereof;

FIG. 4 is a bottom plan view thereof;

FIG. 5 is a top plan view thereof; and,

FIG. 6 is a rear elevational view thereof.
